UNITED STATES PATENT OFFICE.

HORATIO S. EARLE, OF DETROIT, MICHIGAN.

DESIGN FOR A BLADE FOR GRASS-HOOKS.

59,072.

Specification for Design.

Patented Sept. 20, 1921.

Application filed September 12, 1918. Serial No. 253,833. Term of patent 14 years.

To all whom it may concern:

Be it known that I, HORATIO S. EARLE, a citizen of the United States, and resident of Detroit, in the county of Wayne and State of Michigan, have invented a new, original, and ornamental Design for Blades for Grass-Hooks, of which the following is a specification, reference being had to the accompanying drawings, forming a part thereof.

Figure 1 is a plan view of a blade for grass hooks showing my new design.

Fig. 2 is an edge view taken from the back of the blade.

Fig. 3 is a view taken from the heel of the blade at a right angle to the line α of Fig. 1.

I claim—

The ornamental design for a blade for grass hooks substantially shown and described.

HORATIO S. EARLE.
